JOHN GELOSO, OF NEW YORK, N. Y., ASSIGNOR TO PILOT ELECTRIC MANUFACTURING COMPANY, INC., OF BROOKLYN, NEW YORK, A CORPORATION OF NEW YORK

SWITCH

Application filed June 5, 1929. Serial No. 368,463.

This invention relates to improvements in switches for electrical control, being particularly directed to a device capable of application in radio reception mechanisms.

5 Broadly, it is an object of this invention to provide for a novel form of switch, of the snap switch type, comprising of a crank actuated contacting member, enclosed in an insulating medium, as for example a casing 10 formed of a phenolic condensation product, which contact member is displaceable angularly on a bearing surface, upon which it is pivoted upon the actuation of the control operating the crank.

15 Still further, it is an object of this invention, to provide for a novel type of interconnection crank control member, and the movable contact making member, comprising of a resilient element, attachable to the said 20 crank, and said contact member, the said resilient element, being adapted to be mounted at the respective extremities of the crank and the contact making member, so that the contact making member, may be readily 25 placed about its pivot, upon actuation of said crank.

Still further, it is an object of this invention to provide for a novel form of snap switch, comprising of a minimum of elements, positioned within the casing, and which elements are assembled in association with one another, through separable interconnections, whereby assembly of the constituent elements of the switch may be carried 35 out with a minimum of time and a maximum of efficiency.

These and other advantages, capabilities and features of the invention will appear from the subjoined detailed description of 40 one specific embodiment therefor illustrated in the accompanying drawings, in which:

Figure 1 is a side elevation in section of the device;

Figure 2 is a front view of the device, looking along lines 2-2 of Figure 1;

Figure 3 is a rear view of the device;

Figure 4 is a front elevation of the interior of one half of the device, with the cover removed;

50 Figure 5 is a front elevation of the inte-

rior of the other half of the device with the cover removed; and

Figure 6 is a plan view in section along lines 6-6 of Figure 2.

Referring to the reference characters in the drawing, numerals 10 and 11 represent two hollow associated shells, each of which forms half of the complete enclosing casing, the said shells being fabricated of a phenolic condensation product.

Referring particularly, to the structure in Figure 1, the casing is mounted to the rear of the front panel 12, of a radio receiver through the medium of a single mounting support.

The single mounting support comprises 65 a hub or bearing member 13, fixed to the top of shell 11, at one end 14, of the shoulder as by means, of being molded directly into the shell in the fabrication thereof, the shoulder being threaded as at 15, and passing 70 through aperture 16, formed in the front panel, there being provided a nut 17, to lock both the shoulder and the casing to which it is fastened to the panel, by means of the cooperation of the interior threading of the nut, 75 with the exterior threads of the shoulder 13.

A spindle 18 is adapted to be carried for rotation within the interior of the shoulder or bearing 13, which spindle has fastened at one end thereof, the knob control member 19, 80 as by means of a set screw, and which spindle member has fastened at its other hollowed end, the vulcanized fiber crank member 20, through the upsetting or heading of the ears 21, of the spindle thereagainst, as shown in 85 Figure 5. A washer 22, is mounted on the spindle 18, so as to separate the crank from the inner top wall of the shell 11,

On the spindle there is mounted as by riveting a projection or lug 23, having a grooved portion over which there is adapted to pass for connection one end or loop 24, of the spring member 25, the other end of which spring member is adapted to be fastened 95 to the contact making member, as will be later described. A barrier or baffle 26, is positioned in shell 11, in the terrace section thereof, to prevent electrical contact or short circuiting between and through the contact 100

making member, and the remaining elements of the mechanism.

In the shell member 10, there are positioned two terminals 27 and 28, comprising of threaded screws, which screws are adapted 5 to pass through apertures 29 and 30, in the top of shell 10, the screws and washers associated therewith, being adapted to be molded directly into the shell 10, during the fabrication thereof, whereby the head 32 of terminal 10, 15 is adapted to contact and fixedly position a unitary triple right angular flexible metallic strip 33, the end extremity of which rests against the inner end wall of the shell 10, in a groove formed in the hollowed interior of shell 10. The strip 33 is adapted to have cooperating therewith, the contact making member 34, which is mounted in the grooved portion 35, of the projection of terminal 28, within the shell 10, the enlarged head 36, of the terminal being formed at the extremity of said projection adjacent the groove in which the contact making member 20 is pivoted, in order to restrain the contact making member from lateral displacement. 25

The contact making member as shown clearly in Figures 1, 4 and 5, comprises of an integral resilient metallic stamping, having one end portion 37, in the shape of an arrow, 30 one side of which arrow is adapted to contact with the end extremity 33' of the fixed contact strip 33, and the other end of which contact making member comprises a projection 38, perpendicularly disposed with respect to the remainder of the contact making element, and having a grooved portion 39, therein, into which there is adapted to be positioned the loop 40, forming the second extremity of the spring member 25. The contact making member has a central aperture 41, of a greater cross sectional area, than the head 36, formed on the fixed terminal 28, so as to be readily positioned in the grooved portion 35, of said projection, the contact making element, being always adapted however, to be disposed in said grooved portion 35, due to the action of the compression spring 25, urging it upwardly when the device is assembled, as is seen in Figures 1 and 40 45 50 55 60 65

As shown in Figure 5, the displacement of the crank and the contact making member actuated thereby through the medium of the interconnecting elements, is controlled as to a degree, by the contact of the extremities 42 and 43, of the crank end with the side walls of the shell 11, whereby the arrow portion 37, of the contact making member is either urged against the end extremity 33' of the contact strip 33, when actuated in one direction by the crank upon rotation of the knob, 70 75 80 85 90 95 100 105 110 115 120 125 130

or is urged to the other side of shell 10, out of contact with the fixed contact 33, upon the actuation of the cam member and the knob controlling the same in the opposite direction.

As is obvious, circuit connections are made by the contact making member, between fixed contacts 27 and 28, when the contact making member 34, is in position indicated in Figure 4.

The screw and nut assembly 44 and 45, is used to unite the two shells 10 and 11, to form the complete casing and nuts 46 and 47, are adapted to fasten contacts for the exterior circuits to the contact members 27 and 28.

As can be seen from the disclosure, the mechanism comprises a series of simple elements easily assembled, easily separated and easily displaced, and/or replaced, making possible the efficient assembling and introducing a considerable simplicity of the structure over the prior type of switches.

It is obvious that various changes and modifications may be made to the details of construction without departing from the general spirit of the invention as set forth in the appended claims.

Claims:

1. A switch comprising a casing, a plurality of fixed terminals extending therefrom, a fixed contact mounted in the casing, in electrical contact with one of said terminals, a movable contact pivoted on the other of said fixed terminals, a crank and resilient means interconnecting the crank with one extremity of said movable contact, and a spindle fixed to said crank, a knob for actuating said spindle, stop means for limiting the displacement of the said crank, said movable member, being displaceable about its pivot, into and out of contact with the fixed contact, upon the rotation of said spindle.

2. A switch comprising a casing, a plurality of fixed terminals positioned thereon, a fixed contact mounted in the casing in electrical contact with one of said terminals, a movable contact pivoted on the other of said fixed terminals, a crank member, rotatable within said casing, a knob interconnected with said crank for rotating the same, a projection on said crank, a projection at one end of said movable contact, resilient means interconnecting the projections on the crank and on the movable contact, said crank being of such formation as to contact with the opposite walls of the casing, said movable contact member being displaceable to a degree proportionate to the displacement of the crank member, and a projection on said movable contact, the said projection being adapted to contact with the fixed contact, in order to make an electrical circuit connection upon displacement of the crank in one direction, said contact member adapted to be movable in

the opposite direction, to break the electrical circuit when the crank is displaced in a direction opposite to its original displacement.

3. A switch comprising a casing, a plurality of fixed terminals positioned therein, a fixed contact mounted within the casing, in electrical contact with and supported by one of said fixed terminals, a movable contact pivoted about the other of said fixed terminals, a control knob and a crank operable thereby for displacement in either direction, and resilient means interconnecting the crank and the movable contact member, whereby actuation of said knob causes displacement of said movable contact into and out of physical and electrical relation with said fixed contact.

4. A switch comprising a casing, a plurality of fixed terminals positioned therein, a fixed contact mounted within the casing, in electrical contact with and supported by one of said fixed terminals, a movable contact plate pivoted about the other of said fixed terminals, a control knob and a crank operable thereby for displacement in either direction, and means interconnecting the crank and the movable contact member, whereby actuation of said knob causes displacement of said movable contact into and out of physical and electrical relation with said fixed contact, said crank being of such shape, whereby the opposite sides thereof, contact with the opposite side walls of the casing, whereby to limit the displacement of the crank and the movable contact member.

5. A switch comprising a casing, a plurality of fixed terminals, positioned therein, one of said fixed terminals having a fixed contact plate mounted thereon, said fixed contact being shaped so that one end thereof is positioned adjacent one side wall of said casing, a movable contact member pivoted on the other of said fixed terminals, a crank member mounted in said casing, a resilient member connecting one end of said movable contact with said crank, the other end of said movable contact being offset and adapted to contact with the extremity of the fixed contact plate upon displacement in one direction thereof, and with the opposite side wall of the casing upon displacement in the opposite direction thereof.

6. A switch comprising a casing, a plurality of fixed terminals, positioned therein, one of said fixed terminals having a fixed contact plate mounted thereon, said fixed contact plate being shaped so that one end thereof is positioned adjacent one side wall of said casing, a movable contact member pivoted on the other of said fixed terminals, a crank member mounted in said casing, a resilient member connecting one end of said movable contact with said crank, the other end of said movable contact being offset and adapted to contact with the extremity of the fixed con-

tact plate upon displacement in one direction thereof, and with the opposite side wall of the casing upon displacement in the opposite direction thereof, and means for actuating the crank member, said crank member being formed so as to contact with the respective side walls of the casing, to limit its movement and the movement of the movable contact member.

7. A switch comprising a casing, a plurality of fixed terminals extending therefrom, a fixed contact mounted in physical contact with one of said terminals, a movable contact pivoted on the other of said fixed terminals, a spindle journaled in said casing, and having a control knob at one end thereof, and a crank at the other end thereof, a projection on said crank and a projection formed on one end of said movable contact, a resilient connection positioned therebetween, whereby the rotation of said knob controls the displacement into and out of contact of the free end of the movable contact with the fixed contact.

8. A switch comprising a casing, a plurality of fixed terminals extending therefrom, a fixed contact mounted in physical contact with one of said terminals, a movable contact pivoted on the other of said fixed terminals, a spindle journaled in said casing, and having a control knob at one end thereof, and a crank at the other end thereof, a projection on said crank and a projection formed on one end of said movable contact, a resilient connection positioned therebetween, whereby the rotation of said knob controls the displacement into and out of contact of the free end of the movable contact, with the fixed contact, and an insulated baffle plate, between said spindle, and said resilient member, to prevent the physical and electrical contact therebetween.
